REGINALD B. MELLER, OF ALAMEDA, CALIFORNIA, ASSIGNOR TO THE PARAFFINE COMPANIES, INC., OF SAN FRANCISCO, CALIFORNIA, A CORPORATION OF DELAWARE.

DISPLAY STAND.

Application filed January 8, 1924. Serial No. 684,966.

My invention relates to display stands and particularly to advertising display stands.

An object of my invention is to provide a device which can be folded into a compact 5 package when not in use, and which can be made into a stable stand for display purposes.

Another object of my invention is the production of a display stand comprising a plurality of perspective surfaces from a single 10 sheet of material.

The invention possesses other objects and features of advantage, some of which, with the foregoing, will be set forth in the following description of the preferred form of 15 my invention which is illustrated in the drawings accompanying and forming part of the specification. It is to be understood that I do not limit myself to the showing made in said drawings and description, as I may 20 adopt variations of the preferred form within the scope of my invention as set forth in the claims.

Referring to the drawing:

Figure 1 is a plan view of a flat piece comprising 25 my display stand as it appears before folding. The dotted lines indicate fold lines and the heavy full lines indicate the severed outline of the design displayed by my stand.

Figure 2 is a perspective view of my display stand in folded position.

Figure 3 is a vertical sectional view of the display stand, the plane of section being indicated by the line 3—3 of Figure 1.

Figure 4 is an end elevation of the device when folded into a flat package. The sides are shown slightly parted to illustrate the respective positions of the various portions of the sheet.

Generally speaking, my invention comprises a generally regular quadrilateral sheet of material, such as cardboard creased transversely to permit folding into a flat compact package or a stable display stand. When 45 folded into the form of a display stand, certain perspective surfaces are formed for displaying the advertising matter which is the function of the device, and in order to present additional perspective surfaces and extend one or more of those previously formed, the sheet is cut so as to partially sever portions and these portions form the desired additions.

In detail, my invention comprises a gener-

ally regular quadrilateral sheet of fibrous 55 material, preferably paper board, with transverse creases 2 and 3 and transverse aligned creases 6 and 7, and 8 and 9, extending inwardly from opposite sides of the sheet to the slits 12 and 13 respectively. These creases 60 divide the sheet into areas 14, 16, 17, 18 and 19. Extending over the areas 16, 17, 18 and 19 which include the perspective surfaces, advertising or other matter is displayed, and the area actually covered by such matter is severed 65 from the area 16 by the slit 12, and from the area 19 by the slit 13 which extends beyond the aligned creases 8 and 9 into the area 18 to the fold line 21 extending in the area 18 in substantial parallelism with the fold line 2. 70

The sheet is folded along the creases 2 and 3 and the outer portion of the area 19 is adhesively secured to the area 14. A continuous sheet in the form of a flat two-layer package is thus provided which requires little 75 storage space and which is conveniently packed for shipping. The severed portions on which the subject matter of the display appear lie within their original planes at this time. 80

There are many types of advertising display stands now being used but such devices have objectionable features. They frequently comprise a number of separate pieces and there is always the danger that the device will be improperly assembled or that a part will be lost. In some cases the different parts of the stand are held together by strips adhesively secured to each of the surfaces. The production of such a stand is costly, as much 85 hand work is required. Also many of the stands now being used are not stable and require additional support. If they are stable it is usually impossible to take them down and they are cumbersome to handle, require a large storage space and are difficult to pack for shipping. My invention provides a stand which can be produced very cheaply, can be folded into a one-piece, two-layer package for shipping or storage, and which can 90 almost instantly be made into an attractive stable display stand and as readily knocked down into flat form. 95

To form the display stand of my invention the two-layer package is opened, and the partially severed portion 22 secured at the fold line 21 is lifted from its position within the area 19 so that when the aligned creases 6 and 100

7, and 8 and 9 are folded this partially severed portion extends from the stand forming a perspective surface. When folded into this form the areas 17 and 18 form two perspective surfaces at different angles to the horizontal, the perspective surface 18 being substantially vertical. This perspective surface is broken by the partially severed portion 22 which extends therefrom. The partially severed portion 23 then appears as an extension of the perspective surface 17.

Thus it will be seen that my invention provides a display stand comprising a plurality of perspective surfaces in different angular relation to the horizontal, so that an observer when viewing the matter displayed will see the various elements of the design in their perspective relationships.

In some instances it may be desirable to set an actual specimen for example a carton 29 of the subject matter displayed in close proximity to the perspective planes. For such purpose I have provided the recesses 26 and 27 and at the option of the user, such recesses provide space in which the object may be seated. An object so placed then appears as part of the display and serves to immobilize the stand.

I claim:

30 1. A sheet having opposite ends fixedly joined to form a structurally continuous band and provided with creases to permit the folding of the sheet into a stable display stand having a plurality of continuous areas on which a display is shown with its elements in perspective, said sheet having a portion partially severed from more than one of said areas and joined to one of said areas by a crease separate from the creases provided for the folding of the sheet, all of said areas lying in different planes to accentuate the perspective relationships of the elements of said display.

45 2. A sheet having opposite ends fixedly joined to form a structurally continuous band and provided with creases to permit the optional folding of the sheet into a flat package or into a stable display stand having a plurality of continuous areas one of which is substantially vertical, a portion partially severed from said sheet and directly attached to and extending from said substantially vertical area, a pictorial display having its elements in perspective arranged on said areas, said areas lying in different planes to accentuate the perspective relationships of the elements of said display.

55 3. A sheet having opposite ends joined and

provided with creases to permit the optional folding of the sheet into a flat package or into 60 a stable display stand having a plurality of continuous perspective areas, each carrying a related pictorial display, said areas lying in different planes to accentuate the perspective relationship of the elements of said display, said sheet being provided with a recess 65 to permit the seating alongside the stand and within the perspective areas of an object which is the subject of said design.

4. A sheet having opposite ends joined to 70 provide a continuous band and provided with creases to permit the folding of the sheet into a stable display stand having a plurality of continuous perspective areas, two of which lie at an angle to the horizontal, and one of which 75 is substantially vertical, a portion partially severed from said sheet and extending from said substantially vertical area, another portion partially severed from said sheet and forming an extension of one of said two areas, 80 a display design having its elements in perspective arranged on said display areas, the angular relation between said areas accentuating the perspective relationships of the elements of said display. 85

5. A sheet having opposite ends fixedly joined to form a structurally continuous band and provided with creases to permit the folding of the sheet into a stable display stand having a plurality of continuous areas on 90 which a display is shown with its elements in perspective, said sheet having a portion partially severed from one of said areas, and another portion partially severed from two adjacent areas, all of said areas lying in different planes to accentuate the perspective relationships of the elements of said display. 95

6. A sheet having opposite ends fixedly joined to form a structurally continuous band and provided with creases to permit the folding of the sheet into a stable display stand having a plurality of continuous areas on which a display is shown with its elements in perspective, said sheet having a portion partially severed from one of said areas, and another portion partially severed from two adjacent areas and joined to one of said adjacent areas by a crease separate from the creases provided for the folding of the sheet, all of said areas lying in different planes to 100 accentuate the perspective relationships of the elements of said display. 105

In testimony whereof, I have hereunto set my hand.

REGINALD B. MELLER.
